LAMINATED GRIPPING DOG

Chester M. MacChesney, Chicago, Ill., assignor to
Acme Steel Company, Chicago, Ill., a corpora-
tion of Illinois

Application October 31, 1940, Serial No. 363,675

1 Claim. (Cl. 24—134)

This invention relates to improvements in gripping dogs, and its purpose is to provide improved means adapted for use on strap stretching and sealing devices, and on other tools, for securely holding a metal strap or other binder in fixed position with respect to a part of the tool. It has been common practice to provide tools of this kind with pivoted gripping dogs adapted to hold the strap or binder against a flange or base plate seated on the box, package or other object to be bound, and these dogs have been actuated by gravity or by springs in order to force them into initial engagement with the strap or binder. In order to hold a flat metal strap properly, it is desirable that the gripping dog be substantially coextensive in width with the strap, and this has been the usual practice, but it has been found that such a dog frequently fails to hold the strap securely throughout its width because of variations in the gauge of the metal strap between its edges. As a result of this uneven thickness, or as a result of bending of the part on which the strap rests, the strap may be gripped only at one edge, for example, and when tension is exerted upon the strap it may slide beneath the dog or the excessive tension created in one side portion of the dog may cause it to fail.

The principal object of the present invention is to overcome the foregoing difficulty by providing an improved laminated gripping dog comprising a plurality of relatively movable parts which may adjust themselves to the uneven thickness or contour of the strap or binder being held and thereby exert a gripping action throughout the width of the dog. Another object is to provide a pivoted gripping dog made up of a plurality of laminations arranged edge-wise to the surface to be gripped and provided, preferably, with means for normally moving them independently of each other toward the article to be gripped. A further object is to provide a gripping device comprising a base flange adapted to support a strap and having mounted in fixed relation thereto a pivoted laminated gripping dog provided with resilient means for forcing the laminations into engagement with the strap and with means for simultaneously moving all of the laminations away from the strap when it is desired to effect the release of the strap. Another object is to simplify and cheapen the cost of construction of the device by providing a gripping dog made up of a series of simple flat stampings, thus saving the cost of accurately machining the member. Other

objects relate to various features of construction and arrangement which will appear more fully hereinafter.

The nature of the invention will be understood from the following specification, taken with the accompanying drawings, in which two embodiments are illustrated. In the drawings,

Fig. 1 shows a top plan view of a portion of a tool having embodied therein one form of the improved gripping device of the present invention;

Fig. 2 shows a side elevation of the apparatus illustrated in Fig. 1;

Fig. 3 shows an end elevation of the apparatus illustrated in Figs. 1 and 2, looking toward the left, as viewed in Fig. 2;

Fig. 4 shows a perspective view of the spring by which the individual laminations of the structure shown in Figs. 1 and 2 are forced into normal engagement with the strap to be gripped;

Fig. 5 is a perspective view of one of the individual laminations which make up the composite gripping dog shown in Figs. 1, 2 and 3;

Fig. 6 shows a perspective view of the operating lever by which all of the laminations of the gripping dog shown in Figs. 1, 2 and 3 may be moved simultaneously out of engagement with the strap against the action of the spring shown in Fig. 4;

Fig. 7 is a partial top plan view, similar to that of Fig. 1, showing a modified form of the invention;

Fig. 8 shows a side elevation of the apparatus illustrated in Fig. 7; and

Fig. 9 is a horizontal detail section taken on the line 9—9 of Fig. 8.

In Figs. 1 to 6, inclusive, the invention is illustrated as being applied to a strap stretching or sealing tool or other device embodying a frame 10 adapted to rest upon the box, package or other object to be bound and having a forwardly extending base flange 10a upon which one end of the flat metal strap 11 is adapted to seat. This frame may preferably be provided with an arm 10b extending parallel to the strap and provided at its end with a forwardly extending flange 10c over which the strap 11 extends in passing around the box or package. The flange 10c serves as a support for preventing the tilting of the tool during the operation of the mechanism carried by the frame 10. The strap 11 is adapted to be held upon the flange 10a by a gripping dog 12 which is pivotally mounted upon a pin 13 secured in the frame 10, as shown in Fig. 3, and provided at its outer end with an en-

larged head 13^a. The gripping dog is made up of a plurality of laminations 12^a which are preferably substantially identical and which are arranged in parallel relationship and capable of relative movement about the pivot pin 13. Each lamination of the gripping dog is provided with a serrated gripping surface 12^b which is located in a position at one side of a vertical plane passing through the axis of the pin 13 and these laminations may vary in position on different laminations so they have a staggered relationship when the laminations are assembled. The gripping dog thus has, in effect, an inclined position between the pin 13 and the base flange 10^a so that, when the strap 11 is inserted between the dog and the flange, a pull upon the strap 11, toward the right as viewed in Fig. 2, will tend to increase the grip of the dog upon the strap. These laminations may be formed quickly and cheaply by stamping them from sheet steel or the like.

In order to cause the laminations of the gripping dog to move normally into engagement with the strap, there is provided a spring 14 comprising an upright portion 14^a which is secured by screws 15 to an arm 10^d which extends outwardly from the frame 10 parallel to the pin 13. This spring 14 is reversely bent so that it has an inverted U-shaped configuration and the body portion 14^a is reinforced and stiffened by a flat supporting plate 16 of rectangular form which is secured to the arm 10^d on the outer side of the portion 14^a of the spring. The opposite downwardly extending part of the spring is slotted in a vertical plane to provide a plurality of parallel resilient fingers 14^b each of which is adapted to contact with the end face 12^c of one of the laminations 12^a of the gripping dog. These fingers 14^b are adapted to rotate the laminations 12^a independently of each other about the pin 13 so that they are moved normally to the positions shown by full lines in Fig. 2 where their serrated gripping surfaces 12^b engage the upper side of the strap 11.

In order to move all of the laminations of the gripping dog in a clockwise direction against the compression of the spring 14 for the purpose of releasing the strap 11, there is provided an operating lever 17 which is pivotally mounted on the pin 13 adjacent the head 13^a. This operating lever has the form shown particularly in Fig. 6 where it is illustrated as comprising a vertical body portion 17^a provided with an aperture adapted to be closely fitted by the pin 13. From the upper end of this body portion there extends an operating handle portion 17^b which is adapted to be engaged by the fingers of the operator for the purpose of moving the lever about its pivot. From the lower part of the body portion beneath the handle, an arm 17^c extends inwardly to contact with the faces 12^d of the laminations of the gripping dog, as shown particularly in Figs. 2 and 3. By pressing down on the handle portion 17^b of the operating lever, the arm 17^c will be caused to rotate all of the laminations of the gripping dog about the pin 13, thus pressing the fingers 14^b of the spring toward the left, as shown by dotted lines in Fig. 2 where the gripping surfaces of the laminations are shown by dotted lines as being out of contact with the strap. When the gripping dog laminations are thus elevated, the strap may be inserted or released and then, upon releasing the handle 17^b, the spring 14 will automatically return the laminations of the gripping dog to their gripping positions and

the motion of the gripping dog will at the same time return the lever 17 to its normal position, shown in Fig. 2. The rotation of the lever 17 in a counterclockwise direction is limited by a pin 18 projecting from the frame which is adapted to contact with the free end of the arm 17^c formed on the lever if an excessive movement of the lever occurs. The lever is thus retained at all times in a position where it may be conveniently engaged by the fingers of the operator. The resilient fingers 14^b act independently of each other to move the laminations of the gripping dog into engagement with the strap and thus the strap is gripped throughout its width regardless of variations and irregularities in its contour or thickness.

The form of the invention illustrated in Figs. 7, 8 and 9 differs primarily from the form described above in the character of the means which are provided for moving the laminations of the gripping dog normally into engagement with the strap. In this form, a frame 20 is provided with a forwardly extending base flange 20^a upon which the strap 21 is adapted to seat, and this strap is held in engagement with the flange 20^a by a gripping dog 22 made up of a plurality of parallel laminations 22^a of identical configuration which are pivotally mounted upon a pin 23 secured in fixed position in the frame 20. Each lamination 22^a is provided with a serrated gripping surface 22^b which is located at one side of a vertical plane containing the axis of the pin 23 so that a pull upon the strap toward the right, as viewed in Fig. 8, will cause the laminations to increase their grip upon the strap while a pull upon the strap in the opposite direction will tend to release the strap from the gripping dog.

The laminations of the gripping dog 22 are moved normally into engagement with the upper side of the strap 21 by a spring-pressed plunger 24 which is mounted to reciprocate in the guideway 25^a of a block 25 secured to the side of the frame 20 by screws 26. The guideway 25^a is closed at its inner margin by the frame 20 and at its outer side by a plate 27, and within the chamber thus formed there is mounted a coil spring 28 which bears at one end against the end wall of the guideway while the other end thereof is seated in a circular recess 24^a formed in the plunger 24. This plunger is provided with upper and lower longitudinally extending flanges 24^b which receive between them a block 29 formed of rubber or other resilient deformable material which is secured in place on the plunger in any suitable manner and which is provided on its projecting end with a flat face 29^c adapted to contact with the upright end faces 22^c of the laminations 22^a of the gripping dog. The spring 28 will actuate the plunger 24 to cause all of the laminations to be forced toward a position where they engage the strap 21 and the rubber block 29 will permit such relative angular adjustment of the laminations 22^a as may be necessary to cause the gripping surfaces of all of the laminations to engage the strap regardless of the thickness and surface configuration of the strap at different points throughout its width.

The laminations 22^a of the gripping dog 22 are adapted to be moved simultaneously out of engagement with the strap 21 by means of an operating lever 30 which is identical in form with the operating lever 17 previously described, having a body portion 30^a pivoted on the pin 23 and provided with a handle portion 30^b adapted to be engaged by the fingers of the operator. This

body portion 30^a carries an inwardly extending arm 30^c which is adapted to contact the upright faces 22^d of the laminations, when the lever is moved angularly in a clockwise direction, thereby moving all of the laminations out of engagement with the strap. The reverse angular movement of the laminations 22^a under the influence of the spring 28 may be limited by a pin 31 mounted in the frame and adapted to contact the upper side of the arm 30^c, as in the form of the invention first described.

Although certain forms of the invention have been shown and described by way of illustration, it will be understood that it may be embodied in various other constructions without departing from the scope of the appended claim.

I claim:

The combination in a gripping device, of a frame carrying a base flange, a gripping dog pivotally mounted on said frame and comprising a plurality of relatively movable laminations each adapted to engage a strap seated on said flange, an arm extending outwardly from said frame, a spring of inverted U-shaped cross section having one side attached to said arm and having the other side slotted to form a plurality of separate resilient fingers each engaging one of said laminations, and a lever pivotally mounted on said frame and having a part adapted to engage all of said laminations for forcing all of said laminations away from said flange.

CHESTER M. MACCHESNEY.
